FOLDING TABLE

William H. York, Newark, N. J.

Application April 9, 1938, Serial No. 201,023

4 Claims. (Cl. 311—90)

This invention relates to improvements in folding tables; and the invention has reference, more particularly, to improvements in that type of folding table wherein the top comprises hinged sections adapted to fold together, and wherein means are provided for causing the table legs to automatically fold and unfold in company with the corresponding folding movements of the table top.

10 This invention has as an object to provide, in a folding table of the type above mentioned, an improved means for operatively interconnecting hinged legs with the foldable sections of the table top, whereby the movements of the latter are transmitted to the former and so translated as to cause the legs to simultaneously fold or unfold as the top is folded or unfolded.

The invention has for a further object to provide a novel arrangement and construction of 20 leg moving and controlling means to be actuated by the foldable table top sections, and which additionally operate to firmly hold the legs in either their folded or unfolded condition, as the case may be.

25 Other objects of this invention, not at this time more particularly enumerated, will be understood from the following detailed description of the same.

An illustrative embodiment of the invention is 30 shown in the accompanying drawings, in which:

Fig. 1 is a bottom plan view of the foldable table according to this invention shown in open condition; Fig. 2 is a sectional view, taken on line 2—2 in Fig. 1; Fig. 3 is another sectional view, 35 taken on line 3—3 in Fig. 2; Fig. 4 is a bottom view similar to that shown in Fig. 1, but showing the table in the process of being collapsed to folded up condition; and Fig. 5 is a perspective view of the table in folded up condition, this view 40 being drawn on a somewhat reduced scale.

Similar characters of reference are employed in the above described views, to indicate corresponding parts.

The novel folding table according to this invention comprises a pair of hingedly connected table top sections A and B. Each such top section comprises a rectangular top frame formed by an inner rail 10, an outer rail 11, and connecting end rails 12, suitably joined in frame forming relation. Said inner rails 10 of the respective top frames are laterally opposed in somewhat spaced apart relation, as determined by spacing blocks 13 suitably secured to one or the other thereof, and said top frames are foldably connected together by hinge members 14 affixed

to and between the opposed inner rails 10 thereof. Suitably secured to the upper sides of said top frames are table top members 15, the inner meeting margins of which are preferably provided with interfitting portions comprising, a male edge portion 16 at the margin of one of said top member, and a female edge portion 17 at the margin of the other top member; said male edge portion being adapted to enter the female edge portion when said top members 15 are swung into 10 open condition to occupy a common extended plane (see Fig. 2).

Leg members 18 are pivotally connected with the top frame of table top section A respectively adjacent to the junctures of the outer and end 15 rails of said section A. The pivotal connections for said leg members 18 are provided by pivoting rods 19 which are affixed to and extend between the inner and outer rails 10 and 11 adjacent to the end rails 12 of the top frame of 20 table top section A. Said leg members 18 are relatively off-set one to the other, so as to pass one another when folding to collapsed condition in which they lie parallel to the outer rail 11 and to each other. Preferably means are provided to 25 form receiving compartments 20 for said leg members 18 when the same are infolded, such means comprising partition members 21 secured to and extending between the end rails 12 of the top frame of table top section A. 30

In like manner, leg members 22 are pivotally connected with the top frame of table top section B by corresponding pivoting rods 19, and so as to fold into compartments 20 formed by partition members 21 in connection with the top frame 35 of the table top section B.

The means for actuating the leg members 18 of table top section A are connected with and actuated by movements of the table top section B, and, vice versa, the means for actuating the leg members 22 of table top section B are connected with and actuated by movements of the table top section A. The means for producing outswinging unfolding movements of the leg members 18 of table top section A comprise leg 45 outswinging pull cables 23 which are affixed, by suitable anchoring means 24, to the end rails 12 of the top frame of table section B at points intermediate the inner and outer rails 10 and 11 of said frame, thence to extend to and through stationary guide means or eyes 25 which are affixed to the end rails 12 of the top frame of the table top section A outwardly of but substantially opposite the leg members 18 to be served thereby, to which the outer ends of said pull cables 23 are 50 55

affixed, by suitable anchoring means 26, at points outwardly or downwardly spaced from the fulcrum connections of said leg members 18 with their pivoting rods 19.

5 In like manner, the means for producing outswinging unfolding movements of the leg members 22 of table top section B comprise leg outswinging pull cables 27 which are affixed, by suitable anchoring means 28, to the end rails 12 of the top frame of table section A, thence to extend to and through stationary guide means or eyes 29 affixed to the end rails of the frame of table top section B, thence passing to the leg members 22 to which the same are affixed, by 15 suitable anchoring means 30.

10 The outswinging pull cables 23 and 27, for correspondingly located leg members 18 and 22 of the respective table top sections A and B, have portions disposed adjacent one to the other. Embracing these adjacently disposed portions of the pull cables 23 and 27 are links 31 to which are 15 respectively connected take-up springs 32, the latter being suitably anchored to anchoring means 31' respectively affixed to the respective inner rails 10 of the top frames of the respective table top sections A and B. These take-up springs 32 serve to take up the slack of said outswinging pull cables 23 and 27 when the latter are relaxed by folding the table top sections A and B 20 into closed together relation.

25 The means for producing inswinging folding movements of the leg members 18 of table top section A, comprise leg inswinging pull cables 33, which are affixed, by suitable anchoring means 34, to the inner side of the inner rail 10 of the top frame of table top section B, extending thence through or across the adjacent inner rails of both top frames at a plane outwardly offset from the plane of the hinge connections therebetween, 30 thence extending to and through stationary guide means or eyes 35 opposed to the inner sides of said leg members 18 in suitably spaced relation to the latter, and thence to affixed connection with said leg members 18, by suitable anchoring means 36, 35 at points outwardly or downwardly spaced from the fulcrum connections of said leg members 18 with their pivoting rods 19. Preferably the guide means or eyes 35 are formed by perforations in diagonally disposed bridge bars 37 which are 40 respectively supported between the outer rail and adjacent end rails of the top frame structure adjacent to the outer or upper face level thereof.

45 In like manner, the means for producing inswinging folding movements of the leg members 22 of table top section B, comprise similar leg inswinging pull cables 38, which are affixed, by suitable anchoring means 39, to the inner side of the inner rail 10 of the top frame of table top section A, extending thence through or across the 50 adjacent inner rails of both top frames at a plane outwardly offset from the plane of the hinge connections therebetween, and thence through guide means or eyes 40 of bridge bars 41 to similar affixed connection at 42 with said leg members 22.

55 In the operation of the table, assuming the same to be in open condition and desired to be folded to closed position, the operator merely lifts and turns the same upside down, and thereupon folds the top sections A and B toward one another, to 60 thus close one upon the other as shown in Fig. 5. As the top sections A and B swing toward each other, the leg outswinging pull cables 23 and 27 are relaxed to the movement of their respective anchor points 24 and 28, as respectively fixed to 65 one section, toward the other section which carries

the legs respectively controlled thereby. As the leg outswinging pull cables 23 and 27 thus relax their pull upon the leg members, the leg inswinging pull cables 33 and 38 are subjected to a pulling tension by the movement of their respective anchor points 34 and 39, as respectively fixed to one section, away from the other section which carries the legs respectively controlled thereby, thus exerting an inward pull upon said leg members which causes the same to swing inwardly 10 about the fulcruming pivot rods 19 to infolded positions within the planes of the top frames to which they are connected. These operations will be understood from an inspection of Fig. 4. It will be observed that during the described infolding movements of said leg members, the relaxation of the outswinging pull cables will permit the leg members to readily respond to the pulling movements of the inswinging pull cables. The slack of said outswinging pull cables when thus relaxed is 15 immediately taken up by the tension of the take-up springs 32, so that the latter cables are drawn within the confines of the closed together table top sections.

20 To open the table for use, the reverse of the above described operations occur, for as the top sections A and B are swung about their hinge connections into an extended common plane, the leg outswinging pull cables 23 and 27 will be caused to exert a pulling effect upon the leg members effective to outswing the same to extended operative relation to the opened out top sections, while at the same time the leg inswinging pull cables 33 and 38 will relax to permit the leg members to 25 fully respond to the pull of said outswinging cables.

20 From the above it will be apparent that a very simple and yet efficient means is provided for translating the movements of hinged together extendible table top sections to leg members attached thereto so that by the single act of folding or unfolding said top sections, the legs will be automatically moved to correspondingly folded or unfolded relations thereto. When the novel table structure is folded up, it is reduced to a very compact bulk, easily handled, and adapted to occupy a minimum of storage space; and at the same time all the operative mechanism will be fully enclosed within the confines of the closed together table top sections. When the table is open and its legs 30 extended, the latter will be braced by the oppositely directed tensions of the outswinging and inswinging pull cables, which thus balance each other and tend to hold the legs steady, and the table firmly supported.

35 Various changes could be made in the above described embodiment of my invention, and many apparently widely different embodiments of the same could be made without departing from the scope thereof as defined by the following claims. It is therefore intended that all matter contained in the above description or shown in the accompanying drawings shall be interpreted as illustrative and not in a limiting sense.

40 I claim:

45 1. A folding table, comprising a pair of hingedly connected top sections, leg members pivotally mounted adjacent to the outer corner portions of each top section so as to fold parallel to each other and to the side of the top section on which 50 they are mounted opposite the hinged side thereof, guided leg outswinging pull cables attached to each leg member to extend to anchored connection with the top section opposite to that which carries the leg members controlled thereby, and 55

- guided leg inswinging pull cables attached to each leg member to likewise extend to anchored connection with the top section opposite to that which carries the leg members controlled thereby.
5. 2. A folding table, comprising a pair of rectangular top-frames carrying top members on their upper sides, said top frames having their inner rails hingedly interconnected, leg members pivotally mounted adjacent to the outer corner portions of said top frames so as to fold parallel to each other and to the outer rails of the latter, a leg outswinging pull cable connected to extend from the outer side of each leg member, cable guide means in outwardly offset relation to each leg member, means to anchor each leg outswinging pull cable to an end rail of a top frame opposite to that which carries the leg member from which the cable extends, a leg inswinging pull cable connected to extend from the inner side of
- each leg member, a cable guide means in inwardly offset relation to each leg member, said leg inswinging cables extending across the top frame inner rails in planes upwardly offset relative to the plane of the hinge connection joining said inner rails, and means to anchor each leg inswinging pull cable to an inner rail of a top frame opposite to that which carries the leg member from which the cable extends.
3. In a folding table as defined in claim 1, including spring means for taking up the slack of said leg outswinging pull cables when the same are relaxed.
4. In a folding table as defined in claim 2, including spring means for taking up the slack of said leg outswinging pull cables when the same are relaxed.

WILLIAM H. YORK.
